UNITED STATES PATENT OFFICE.

CHARLES HERITAGE, OF WARREN, MASSACHUSETTS.

DESIGN FOR INSIDE FACE OF CLOTH.

Specification forming part of Design No. 11,189, dated May 13, 1879; application filed April 11, 1879.
[Term of patent 3½ years.]

To all whom it may concern:

Be it known that I, CHARLES HERITAGE, of Warren, in the county of Worcester and State of Massachusetts, have originated and designed a Pattern for the Inside Face of Cloth commonly called "Coating," of which the following is a full, clear, and exact description, reference being had to the accompanying photographic illustration, making part of this specification.

The illustration fully represents my design, and is sufficient, without further aid, to enable any person skilled in the art to repeat it for practical use.

The colors employed for the different portions of this design may be varied to suit the convenience or taste of the manufacturer.

What I claim is—

The design or pattern for the inside face of cloth called "coating," as shown.

CHARLES HERITAGE.
